CLAIM

The ornamental design for a urinal screen, as shown and described.

DESCRIPTION

FIG. 1 is a front, top, and left side perspective view of a urinal screen embodying our new design.

FIG. 2 is a back, bottom, and right side perspective view thereof.

FIG. 3 is a top view thereof.

FIG. 4 is a bottom view thereof.

FIG. 5 is a back view thereof.

FIG. 6 is a front view thereof.

FIG. 7 is a right side view thereof; and,

FIG. 8 is a left side view thereof.

Broken lines are used to illustrate features of the urinal screen which form no part of the claimed design. In FIGS. 1-8, a central top portion of the urinal screen is claimed, and the remainder of the urinal screen forms no part of the claimed design.
